SIMPLIFIED SELECTIVE CIRCUITS

Harold A. Wheeler, Great Neck, N. Y., assignor to
 Hazeltine Corporation, a corporation of Delaware

Application April 5, 1933, Serial No. 664,478

11 Claims. (Cl. 250—20)

The present invention relates to a radio frequency tuning system for use in connection with radio receiving apparatus of the superheterodyne type.

5 In accordance with this invention a dual coupling is provided between the antenna and tuned circuits, the characteristics of the two coupling components being so chosen that they will be substantially equal and opposite at the intermediate frequency.

10 A superheterodyne radio receiver is particularly sensitive to signals of three frequencies, i. e., the desired signal frequency, the "image frequency", which is that frequency displaced above the local oscillator frequency by the same amount that the desired frequency is displaced below the local oscillator frequency, and the intermediate frequency, which is the difference between desired signal and oscillator frequencies. 15

20 In the past, reception of any except the desired signal frequency has been prevented by the use of a plurality of selective circuits interposed between the signal pickup and the first detector or modulator tube. However, these selective circuits require a plurality of variable tuning elements, which tend to prevent reduction in size and manufacturing costs, while still maintaining a high degree of selectivity. Arrangements 25 have previously been devised for preventing the reception of image frequency signals without requiring numerous selective circuits. It is the object of this invention to provide a simplified selective circuit requiring but only the reception of image frequency signals 30 but also the reception of signals of the intermediate frequency.

35 These and further objects of this invention will become apparent from the following specification and claims taken in connection with the accompanying drawing.

40 In accomplishing the objects of this invention, the modulator or first detector of a superheterodyne radio receiver is selectively coupled to the antenna through an antenna coupling network including a single tunable circuit. The tunable circuit is coupled to the antenna circuit by means of a dual coupling comprising oppositely varying impedances, the transfer effects of which 45 are equal and opposite at the intermediate frequency, thus preventing transfer to the tunable circuit of currents of the said intermediate frequency. In addition, the antenna circuit, together with its included impedances, is made

resonant at a frequency near the lower end of the band of frequencies over which the coupling is adapted to be operated, for the purpose of increasing the response of the entire circuit at the low frequency end of the band and thus 5 permitting a substantially uniform responsiveness of the network throughout the band.

Having thus briefly described the invention, attention is invited to the accompanying drawing, in which:

10 Fig. 1 is a schematic diagram of the input circuit to the first detector or modulator of a superheterodyne radio receiver;

15 Fig. 2 is a schematic diagram showing a modification of the circuit of Fig. 1.

Attention is now particularly invited to Fig. 1 in which the antenna 10 and ground 11 are connected by an antenna circuit 17 consisting of the coil 12, shunted by a small capacitance 13, the lower portion 3—4 of the main tuning inductance 14, the fixed coupling condenser 15 and the volume control resistor 16. The antenna circuit just described, the inductance of which is principally that of the inductance 12, is, together with its associated capacities made 20 broadly resonant to some frequency near the lower end of the band through which the circuit is adapted to be tuned. For example, in the design of a superheterodyne for use in the broadcast band, the antenna circuit 17 might be made 25 resonant at 600 kc. By properly designing the response characteristic of the antenna circuit, the responsiveness of the network may be made to vary with frequency in any desired manner, though in the preferred embodiment described 30 more particularly hereinafter, the responsiveness is made substantially uniform over the band of frequencies.

35 The tunable circuit 18 is composed of the coil 14, the coupling condenser 15, and the variable 40 tuning condenser 19, by which the circuit is tuned to respond to the desired signal frequency. The tuning condenser 19 may be connected mechanically to the controlling element of the oscillation frequency circuit for permitting uncontrol 45 in tuning the receiver over a band of frequencies, in a manner well known in the art.

40 The coupling between the primary or antenna circuit 17 and the tunable secondary circuit 18 is provided by the common inductance 3—4 of coil 50 14, the mutual inductance between the portion 3—4 of the coil 14 and the remainder thereof, and by the series coupling condenser 15. The coupling effects of the two coupling elements vary oppositely with frequency, the inductive 55

component of the mutual reactance coupling varying directly with the frequency of the signals and the capacitive component of the coupling varying inversely with the frequency. The two coupling components are so chosen that their individual coupling effects between the circuits 17 and 18 will be exactly equal and opposite at the frequency to which the intermediate frequency amplifiers are tuned. For example, in a superheterodyne employing a 450 kc intermediate frequency, these couplings are adjusted so as to give zero resultant coupling effect between these two circuits at 450 kc and thereby reduce interference with the desired signals.

15 The coupling condenser 15 should preferably have a capacitance which is from five to thirty times the maximum of the variable condenser 19, in order to prevent an unnecessary reduction of the tuning range of the circuit 18 as the condenser 19 is varied, while still providing sufficient reactance for satisfactory operation.

16 The small capacitance 13, together with coil 12, forms a trap to reduce interference at frequencies higher than the tuning range, but does not materially affect the operation of the circuits toward signal or intermediate frequencies.

20 The grid of the modulator 20 is connected to the tuned circuit 18 by means of the tap 2 on coil 14. The tap 2 is so located that the image frequency voltage is at node potential relative to ground at at least one point in the tuning range of the circuit 18. The position of tap 2 is preferably selected to give best image frequency suppression near the low frequency end 25 of the band. The condenser 21 is for the purpose of making the image suppression which results from the tapped coil 14 more uniform over the entire range and its value is preferably selected to give best suppression near the high frequency end of the band.

40 The modulator 20 should preferably be a screen grid tube in order to insure a purely capacitive grid load on the tapped section of the tuned circuit.

45 The oscillation frequency voltage, which is supplied by an oscillation circuit represented by the oscillation source 22, may be impressed in the cathode circuit of the tube 20 as is usual in superheterodyne circuits. The details of the oscillation circuit constitute no part of this invention and therefore need not be further described.

50 The modulator 20, which converts the incoming audio-modulated carrier-frequency signals into audio-modulated intermediate-frequency signals, has its plate connected through the primary 23 of an intermediate-frequency transformer to the direct-voltage source 24. By this means the audio-modulated intermediate-frequency current is supplied to the intermediate-frequency responsive radio receiver 26 and is amplified therein and reproduced in the usual manner. The screen grid of the tube 20 is supplied with an appropriate voltage by means of the source 24.

55 The details of the remaining circuits of the receiver are well known in the art and need not be further described.

60 Attention is now invited to Fig. 2 which represents a modified arrangement of the input circuits of a superheterodyne radio receiver constructed in accordance with this invention. In this figure, corresponding parts are designated by the same reference characters, with, however, a prime mark added when the values

thereof are different from those of the corresponding part in Fig. 1. In this circuit, the antenna circuit 17 includes a coil 25 which is inductively coupled to the secondary tuning coil 14. The condenser 21', for assisting the image-frequency suppression, is connected as shown to the junction between the antenna inductance 12' and the primary 25. This same junction is connected through a resistor 26 to ground, the function of this resistor being to reduce interference at frequencies higher than the tuning range. The remainder of this circuit is, except for the location of tap 3', similar in all respects to that of Fig. 1.

65 In the arrangement shown in Fig. 2, the inductive coupling between the antenna circuit 17 and the tuned circuit 18 includes the mutual inductance between the primary coil 25 and the secondary inductance coil 14, the mutual inductance between part 3'-4 of inductance coil 20 14 and the remainder thereof, and the self-inductance of part 3'-4 of inductance coil 14. The magnitude of the capacitive coupling provided by the fixed condenser 15 is so chosen, relative to the sum of the inductive couplings, 25 that it will substantially nullify the coupling of said inductive means, and there will be substantially zero resultant coupling between the antenna circuit 17 and the tuned circuit 18 at the intermediate frequency. In this circuit also 30 the antenna circuit is preferably made broadly resonant to a frequency in the lower part of the tuning range, such as 600 kilocycles in a broadcast receiver.

35 Approximately the following circuit constants have been found to produce good results in the circuit of Fig. 1, operating over the broadcast range of 550 to 1500 kc, with an intermediate frequency of 450 kc:

Resistor 16=5000 ohms.

Coil 12=300 microhenries.

Capacitance 13=4 micro-mfd.

Coil 14=240 microhenries.

Section 3'-4 (of coil 14)=18 microhenries.

Mutual inductance, section 3'-4 to remainder 45 (of coil 14)=9 microhenries.

Section 1-2=12% of turns of coil 14.

Condenser 21=260 micro-mfd.

Condenser 15=4700 micro-mfd.

Condenser 19 (maximum)=350 micro-mfd. 50

Approximately the following circuit constants have been found to give good results in the circuit of Fig. 2, under similar conditions:

Coil 12=200 microhenries.

Coil 25=100 microhenries.

Resistor 26=10,000 ohms.

Condenser 21'=8 micro-mfd.

Coil 14=240 microhenries.

Section 3'-4 (of coil 14)=5 microhenries.

Mutual inductance, section 3'-4 to remainder 60 (of coil 14)=7 microhenries.

Mutual inductance, coil 25 to coil 14=15 microhenries.

(Other constants same as for Fig. 1.)

65 Appropriate cathode heating circuits (not shown) are provided for heating the cathode of the tube 20.

70 Whereas this invention has been shown and described in connection with a superheterodyne receiver for broadcast signals, it is to be understood that the invention is equally applicable to receivers or converters operating in any other of the various frequency bands and also to receivers for operation with wire telephony. 75

There is claimed:

1. An antenna coupling network operative over a band of frequencies, including in combination an antenna circuit having connected in series an antenna, a coil and a fixed coupling condenser, a tuned circuit tunable over said band and having connected in series said condenser, a second coil and a variable tuning condenser, and inductance means coupling said circuits in opposition to the coupling provided by said fixed condenser at frequencies below said band, said antenna circuit being broadly resonant at a frequency near the lowest frequency of said band, and said fixed condenser having a value between five and thirty times the maximum capacitance of said variable condenser, said value being proportioned to substantially nullify the coupling of said inductance means at a fixed frequency somewhat below said band.

2. An antenna coupling network operative over a band of frequencies, including in combination an antenna circuit having connected in series an antenna, a coil and a fixed coupling condenser, a tuned circuit tunable over said band and having connected in series said coupling condenser, a second coil and a variable tuning condenser, and inductance means coupling said circuits in opposition to the coupling provided by said fixed condenser at frequencies below said band, said antenna circuit being broadly resonant at a frequency near the lowest frequency of said band, and said fixed condenser having its magnitude proportioned to substantially nullify the coupling of said inductance means at a fixed frequency somewhat below said band.

3. A selective network operative over a band of frequencies, including in combination, primary and secondary circuits and means for coupling said circuits, said means including at least two predetermined coupling elements whose coupling effects vary differently with frequency, and whose resultant coupling effect is substantially zero at a particular fixed frequency outside said band, one of said circuits being tunable over said band, and the other of said circuits being broadly resonant at a frequency near that edge of said band which is closer to said particular frequency, whereby the responsiveness of said network is made substantially uniform over said band of frequencies.

4. A selective network operative over a band of frequencies, including in combination, primary and secondary circuits and means for coupling said circuits, said means including at least two predetermined coupling elements whose coupling effects vary differently with frequency, and whose resultant coupling effect is substantially zero at a particular fixed frequency outside said band, one of said circuits being tunable over said band, and the other of said circuits being broadly resonant at a frequency near that edge of said band which is closer to said particular frequency, whereby the responsiveness of said network is made to vary with frequency in a predetermined manner.

5. In a superheterodyne receiver operative over a band of frequencies and subject to interference at a particular fixed frequency below said band, an arrangement for selectively coupling an antenna to succeeding circuits of said receiver and for reducing said interference, comprising a primary circuit including the antenna, a tunable secondary circuit coupled to said succeeding circuits, and at least two fixed coupling elements,

included in both said primary and secondary circuits, whose coupling effects vary oppositely with frequency and whose resultant coupling effect is substantially zero at the said frequency below said band.

6. In a superheterodyne receiver operative over a band of frequencies and subject to interference at a particular fixed frequency outside said band, an arrangement for selectively coupling an antenna to succeeding circuits of said receiver and for reducing said interference, comprising a primary circuit including the antenna, a tunable secondary circuit coupled to said succeeding circuits, and compound means for coupling said primary and secondary circuits, said compound means including at least two fixed coupling elements whose coupling effects vary differently with frequency and whose resultant coupling effect is substantially zero at said frequency outside said band, at least one of said coupling elements being included in said secondary circuit.

7. In a superheterodyne receiver operative over a band of frequencies and subject to interference at the intermediate frequency, an antenna coupling network for selectively coupling an antenna to the first detector of the receiver and for reducing said interference, said network comprising a primary circuit adapted to include said antenna, a tunable secondary circuit coupled to the first detector, and means coupling said primary and secondary circuits, said means including at least two fixed reactive elements individually coupling said primary and secondary circuits and whose coupling effects vary oppositely with frequency, said reactive elements being so proportioned and arranged that at the intermediate frequency the resultant voltage produced in said secondary circuit by said reactive elements is substantially zero.

8. In a superheterodyne radio receiver operative over a band of frequencies and subject to interference at intermediate and image frequencies, an antenna coupling network for selectively coupling an antenna to the first detector of the receiver and for reducing said interference, said network comprising a primary circuit adapted to include said antenna, a tunable secondary circuit coupled to said first detector, means coupling said primary and secondary circuits, said means including at least two fixed reactive elements individually coupling said primary and secondary circuits and whose coupling effects vary oppositely with frequency, said reactive elements being so proportioned and arranged that at said intermediate frequency the resultant voltage produced in said secondary circuit by said reactive elements is substantially zero, and means included in said network for suppressing signals of said image frequency.

9. In a superheterodyne receiver operative over a band of frequencies and subject to interference at intermediate and image frequencies, an antenna coupling network for selectively coupling an antenna to the first detector of the receiver and for reducing said interference, said network comprising a primary circuit adapted to include said antenna, a tunable secondary circuit coupled to the first detector and means for coupling said primary and secondary circuits, said means including at least two fixed coupling elements whose coupling effects vary oppositely with frequency and whose resultant coupling effect is substantially zero at said intermediate frequency, said coupling elements being

included in said secondary circuit, and means in said network for suppressing signals of said image frequency, said primary circuit being broadly resonant at a frequency near the lowest frequency of said band, whereby the responsiveness of said network is made substantially uniform over said band of frequencies.

10. In a superheterodyne receiver operative over a band of frequencies and subject to interference at a particular fixed frequency outside said band, an arrangement for selectively coupling the antenna to succeeding circuits of said receiver and for reducing said interference, comprising a primary circuit adapted to include said antenna, a tunable secondary circuit coupled to said succeeding circuits, and means for coupling said primary and secondary circuits including at least two fixed reactive elements individually coupling said primary and secondary circuits and the coupling effects of which vary differently with frequency, said reactive elements being so proportioned and arranged that at said frequency outside said band the resultant voltage produced in said secondary circuit by said reactive elements is substantially zero.

11. In a superheterodyne radio receiver operative over a band of frequencies and subject to interference at intermediate and image frequencies, an arrangement for selectively coupling the antenna to succeeding circuits of said receiver and for reducing said interference, comprising a primary circuit adapted to include said antenna, a tunable secondary circuit coupled to said succeeding circuits and means for coupling said primary and secondary circuits including at least two fixed reactive elements individually coupling said primary and secondary circuits and the coupling effects of which vary oppositely with frequency, said reactive elements being so proportioned and arranged that at said intermediate frequency the resultant voltage produced in said secondary circuit by said reactive elements is substantially zero, and means in said network for suppressing signals of said image frequency, said primary circuit being broadly resonant at a frequency near the lowest frequency of said band, whereby the responsiveness of said network is made substantially uniform over said band of frequencies.

HAROLD A. WHEELER.
